(57) **CLAIM**

The ornamental design for a headrail for an architectural covering, as shown and described.

DESCRIPTION

FIG. 1 is an isometric view looking at the top and front of a first embodiment of a headrail showing our new design;

FIG. 2 is a right side view of the first embodiment of the headrail of FIG. 1, the left side view being a mirror image thereof;

FIG. 3 is a front view of the first embodiment thereof;

FIG. 4 is a top view of the first embodiment thereof;

FIG. 5 is a bottom view of the first embodiment thereof;

FIG. 6 is a rear view of the first embodiment thereof; and

FIG. 7 is an isometric view of a second embodiment of the design of FIGS. 1–6;

FIG. 8 is a right side view of the second embodiment of FIG. 7, the left side view being a mirror image thereof;

FIG. 9 is a front view of the second embodiment of FIG. 7;

FIG. 10 is a top view of the second embodiment of FIG. 7, the bottom view of the second embodiment being identical to the bottom view of the first embodiment shown in FIG. 5;

FIG. 11 is a rear view of the second embodiment of FIG. 7; and,

FIG. 12 is an enlarged fragmentary side view taken along the line 12—12 of FIG. 11.
